RHODE ISLAND, A CORPORATION OF RHODE ISLAND.

KNITTING-MACHINE.

No. 818,295.

Specification of Letters Patent.

Patented April 17, 1906.

Application filed November 28, 1901. Serial No. 83,736.

To all whom it may concern:

Be it known that I, JAMES E. ROWE, of Pawtucket, county of Providence, and State of Rhode Island, have invented certain new and useful Improvements in Knitting-Machines; and I do hereby declare the following specification, taken in connection with the accompanying drawings, forming a part of the same, to be a full, clear, and exact description thereof.

The present invention relates to that class of circular-knitting machines which are employed for knitting stockings or half-hose and in which the cam-carrying ring or cylinder is rotated during the formation of the leg or foot of a stocking and is reciprocated during the formation of the pouches or pockets forming the heel or toe, a certain number of needles being thrown out of action during the formation of the heel and toe and individual needles being transferred from the active to the idle series of needles during the narrowing of the heel or toe and being transferred from the idle to the active series during the widening of the heel or toe.

Certain features of invention relate to machines of this class in which the loops are held as the needles rise through them by sinkers or holders, which overlie the loops and hold them as the needles are raised or advanced through the newly-drawn loops. In machines of this character, in which the cam-cylinder is reciprocated during the formation of the heel or toe and in which sinkers are employed for holding the fabric during the advance of the needles through the loops, it has been customary to provide the cam-cylinder with two knitting-cams, one of which acts to draw down the needles during rotary knitting and during the movement of the cam-cylinder in the same direction in reciprocating knitting and the other of which acts to draw down the needles only during the movement of the cam-cylinder in the opposite direction in reciprocating knitting, the cams being located on opposite sides of the thread eye or guide, from which the thread passes to the needles, so that the thread may be led to the needles in front of the wave formed in the series of needles by the knitting-cam. This duplication of the knitting-cams involves the use of a number of switch-cams or other devices for properly di-

recting and guiding the butts of the needles to the proper cams as the cam-cylinder reciprocates back and forth and is also open to the more serious objection of producing an uneven fabric after the machine has been in use a short time and requiring frequent renewals of the knitting-cams. The variation in the parts of the fabric is due to the fact that one of the cams is in operation to a much greater extent than the other and is therefore worn more rapidly, so that it does not draw the needles down to the same extent as does the other cam, with the result that loops drawn by the worn cam are not so long as those drawn by the other cam. Thus after the machine has been in operation a short time the courses of stitches formed on the heel and toe as the cam-cylinder moves in one direction are not of the same size or degree of tightness as the stitches formed as the cylinder moves in the other direction, and the variation increases with the use of the machine until it is so great as to require the renewal of the knitting-cams. These objections to the use of duplicate sets of cams are overcome and a more simple construction also provided by the features of the present invention, which enable the employment of a single knitting-cam which acts to draw down the needles in rotary knitting and also during the movement of the cam-cylinder in both directions in reciprocating knitting.

The employment of a single knitting-cam involves changing the relation of the cam and the point from which the thread is led to the needles, so that the thread shall be led from opposite sides of the cam as the cam-cylinder reciprocates. This is necessary in order that the thread may run to the needles from a point in front of the wave formed in the series of needles by the knitting-cam. In the case of reciprocating sinkers it also involves advancing the sinkers on opposite sides of the knitting-point as the cam-cylinder reciprocates, for the reason that the sinker should be withdrawn in front of the knitting-point where the needles are drawing the loops and should be advanced back of the knitting-point where the needles are rising through the loops. The particular construction and arrangement of the mechanisms by which these results are accomplished are not material to the broad scope

- of these features of invention, which reside in so constructing, arranging, and operating the knitting-cam, thread-guiding means, and the sinkers that the thread will be led 5 from opposite sides of the cam and the sinkers act to hold down the loops on opposite sides of the knitting-point as the cam-cylinder reciprocates. With this construction the needle-butts pass down one side of the 10 knitting-cam as the cylinder moves in one direction and down the other side as the cylinder moves in the opposite direction, the lowest point to which the needles are drawn in each case being determined by the point 15 of the cam, and an even fabric will therefore be produced, although the cam becomes worn. As will be seen, this single knitting-cam constitutes a double-acting stitch-forming cam.
- 20 The devices for operating the sinkers and the devices for changing the thread from one side of the knitting-cam to the other, which will be hereinafter referred to in describing a machine embodying the combinations above referred to, are novel and embody features of invention which may be employed with advantage in machines which do not embody the general organization above referred to. These features will be more fully 25 explained hereinafter and specified in the claims.
- 30 Further features of invention relate to the construction and the manner of operating and controlling the pickers for transferring the needles from the active to the idle series, and vice versa during the narrowing and widening, and to the construction and manner of operating the cams for throwing the needles not used on the heel and toe into and 35 out of operation. These features of invention may be employed in machines having the usual duplicate sets of knitting-cams, as well as in machines embodying the features of invention already referred to.
- 40 Further features of invention relate to the manner of mounting the latch-guard and main thread-guide, these devices being so supported that they are removed with the needle-cylinder, thereby avoiding the withdrawal of the thread from the thread-guide 45 when the needle-cylinder is removed, and the necessity for threading the thread through the thread-guide and leading it to the needles at the proper point when the needle-cylinder is replaced and also avoiding the displacement and consequent readjustment of the latches in removing and replacing the needle-cylinder.
- 50 Further features of invention relate to means for enabling the needles to be leveled 55 below the sinkers when transferring a top to the needles in knitting half-hose and returning the needles to knitting position after the top has been transferred to the needles.
- 60 The further features of invention will be re-

ferred to in the following detailed description of a knitting-head embodying all the various features of the invention, and will be specified in the claims.

For the purpose of illustrating the various 70 features of the invention a knitting-head is shown in the drawings, which embodies all of said features.

In the drawings, Figure 1 is a sectional elevation of a knitting-head and so much of an 75 automatic machine as is necessary for an understanding of the construction and mode of operation of the devices embodying the various features of invention, the section being on line 1 1, Fig. 4. Fig. 2 is a plan view of 80 the latch-ring and sinker cam-ring. Fig. 3 is a detail of the means for operating the needle-controlling cams. Fig. 4 is a plan view of the cam-ring with the needle-cylinder removed. Fig. 5 is a horizontal sec- 85 tional view through the lifting-pickers. Figs. 6 to 9 are details showing the operation of the pickers. Figs. 10 and 11 are views showing the devices for operating the sinkers. Figs. 12 and 13 are views showing the manner of 90 leading the thread to the needles. Fig. 14 is a view showing the under side of the sinker cam-ring. Fig. 15 is a view showing the cams for controlling the sinker-cam. Fig. 16 is a sectional view through the center line of 95 the sinker-cam. Fig. 17 is a sectional view on line 17 17, Figs. 10 and 14. Fig. 18 is a sectional view on line 18 18, Figs. 10, 14, and 15. Fig. 19 is a view showing a development of the inside of the cam ring with the parts 100 in position for rotary knitting. Fig. 20 is a similar view with parts in position for narrowing. Fig. 21 is a similar view with the parts in position for widening. Fig. 22 is a similar view with the parts in position for 105 leveling the needles in transfer work. Fig. 23 is a detail of devices carried by the cam-ring. Fig. 24 is a horizontal section through a guard-cam. Fig. 25 is a vertical section through a guard-cam. Fig. 26 is a section 110 on line 26 26, Fig. 5. Fig. 27 is a plan view of devices carried by the cam-ring. Fig. 28 is a sectional view on line 28 28, Fig. 27; and Fig. 29 is an elevation of the devices shown in Fig. 27.

In the machine shown in the drawings the needles 1 are guided in grooves formed in the outer periphery of a needle-cylinder 2, being held in said grooves by spring-bands 3 in the usual manner. The needle-cylinder is supported by a ring 4, which may be lowered and raised to regulate the length of the stitches or for effecting the transfer of tops to the needles by any suitable mechanism—such, for instance, as shown in Patent No. 565,218, granted August 21, 1900. The needles are provided with the usual butts 5, those needles not used upon the heel and toe being provided with longer butts than the others, as is common. The cams and de- 115 120 125 130

- 5 vices for acting upon the needle-butts to give them the required movements in the operation of the machine are carried by a cam-cylinder 6, mounted to rotate upon a plate 7, and provided with a gear 8, through which the cylinder may be given a continuous rotary movement or a reciprocating movement by any suitable mechanism, such as is well known in the knitting-machine art.
- 10 The needle-butts are supported upon an annular ledge 9, carried by the cam-cylinder. Between the ends of this ledge the devices for reciprocating the needles in the knitting operation and in leveling and returning the 15 needles in transferring are located. The annular ledge, as well as the cams for operating upon the needle-butts, are supported at some distance from the inner surface of the cam-cylinder, so that a free space is left between the cam-cylinder and the ledge and cams carried thereby through which any broken needle-butts may fall downward out of the machine. This construction also enables the pickers to be mounted inside the cam-cylinder. The ledge 9 is secured to bosses 10, projecting in from the cam-cylinder, as shown in Fig. 26. The knitting-cam for drawing down the needles and the coöperating cams for raising the needles are located 20 between the ends of the ledge 9, Fig. 19. The knitting-cam consists of a plate 11, provided with converging cam-surfaces 12 and 13, which engage the needle-butts and force them downward. The coöperating cams consist of plates 14 and 15 arranged on opposite sides of the knitting-cam, the plate 14 having an inclined cam-surface 16 adjacent and parallel to the cam-surface 13, and the plate 15 having a cam-surface 17 adjacent 25 and parallel to the cam-surface 12. When the cam-cylinder rotates in the direction of the arrow, Fig. 19, the needle-butts pass down the surface 12, under the point of the knitting-cam, and up the surface 16. When the cam-cylinder rotates in the opposite direction during reciprocating knitting, the needle-butts pass down surface 13, under the point of the knitting-cam and up surface 17 onto the ledge 9. Thus the knitting-cam 30 and the coöperating lifting-cams form a wave, as shown at 18, Figs. 12 and 13, in the series of needles, which travel continuously around the series of needles during rotary knitting and back and forth across the series of active 35 needles during reciprocating knitting, the position of the wave with relation to the cam-cylinder being substantially fixed since the lowest point of the wave is always formed by the point of the cam-plate 11. Since the 40 needle-butts pass over the point of the same knitting-cam whenever they are drawn down to form the stitches, the stitches will be of the same size throughout the fabric, and the wearing of the knitting-cam will not produce 45 unevenness in the successive courses on the
- heel and toe as in the machines as heretofore constructed with two sets of knitting-cams. The complication due to the use of switch-cams or other devices for guiding the needle-butts to the proper cams is also avoided and the construction greatly simplified and cheapened.
- 50 The sinkers 19 for holding the fabric as the needles rise through the loops last drawn by them are mounted in the usual manner in radial grooves formed in a ring 19^a, secured to the needle-cylinder, the sinkers being also guided in grooves formed in the top of the needle-cylinder and in a ring 20, secured inside the needle-cylinder. The sinkers are 55 provided with the usual hooks or fingers for overlying the fabric and are reciprocated in their guiding grooves by cams carried by a sinker cam-ring 21, mounted to turn on the sinker-ring 19^a, the cam-ring being provided 60 with an annular rib 22, which fits over the outer edge of the sinker-ring, and being held upon the sinker-rings by plates 23, engaging the under side of the ring. The sinkers are held in position with the hooks above the 65 fabric by a rib 24 on the sinker cam-ring, which engages grooves extending laterally through the sinkers, and this rib has a portion constructed to form shifting or adjustable cams for reciprocating the sinkers, the 70 points at which the sinkers are withdrawn and advanced being shifted or adjusted so that the sinkers will properly coöperate with the needles when operated by the single knitting-cam.
- 75 In the particular construction shown the sinker cam or cams are formed by three pivoted blocks 25, 26, and 27, the blocks 25 and 27 being pivoted to the cam-ring and the block 26 being pivoted between the 80 blocks 25 and 27. These blocks form a part of the rib 24, and they may be shifted or adjusted to change the point at which the sinkers are drawn outward. The devices for shifting the cam-blocks will be described in 85 connection with the description of the devices for leading the thread to the needles in the proper manner.
- 90 When the machine is on rotary knitting or the cam-cylinder is moving in the same direction during reciprocating knitting, the wave 18 travels along the needles in the direction of the arrow, Fig. 12, the needles at the right moving downward to loop the thread through the previously-drawn loops 95 and the needles at the left rising through the newly-drawn loops, and the thread should be led to the needles from a point at the right of the point where the loops are drawn—that is, at the right or in advance of the knitting-point, as indicated in said Fig. 12. When the cam-cylinder moves in the opposite direction, as indicated in Fig. 13, the wave 18 travels from right to left, the needles on the 100 left side being drawn down and the needles

- on the right being raised, and the thread should be led to the needles from the left of the knitting-point. In other words, the thread should be guided to the needles in advance of the knitting-point in whichever direction the cam-cylinder is moving. Since in reciprocating knitting the wave in the needles formed by the knitting-cam travels first in one direction and then in the other, the employment of a single knitting-cam involves the use of means for leading the thread to the needles from opposite sides of the knitting-cam or the knitting-point as the cylinder reciprocates. In the construction shown this means comprises a thread-guide which is shifted from one side of the knitting-point to the other as the cam-cylinder reciprocates, so that the thread-guide travels about the needles in advance of the knitting-point as the cam-cylinder moves back and forth about the needle-cylinder. The devices for effecting the movement of the thread-guide and the manner of mounting the guide are novel in themselves and may be employed with advantage in other machines in which it is desired to shift the relative position of the thread-guide and knitting-point. The latch-guard 29, in which the main thread-guide 30 is formed, is pivoted to a post 31, rising from a plate 32, which is secured to a ring 33, mounted in an annular groove in the top of the sinker cam-ring 21. The thread is led from the usual stationary guides through a guide 34 to the main thread-guide 30, and thence passes to the needles, and the vertical position of the thread-guide and latch-ring when in action is determined by an adjustable screw 35, arranged to engage the plate 32. The ring 33 is frictionally held in place upon the sinker cam-ring by friction-plates 36, secured upon the cam-ring and having spring-tongues 37, which bear upon the upper surface of the ring 33.
- The sinker cam-ring is connected with the cam-cylinder through an arm 38, Figs. 1 and 14, projecting from a plate 39, secured to the under side of the sinker cam-ring, the ends of the plate forming two of the plates 23 before referred to. The arm 38 is provided with a recess 40 in its end within which fits the upper end of a shaft 41, carried by the cam-cylinder. The sinker cam-ring, therefore, moves with the cam-cylinder, and the ring 33, which carries the thread-guide 30, also moves with the cam-cylinder, the thread-guide being held in proper relation to the knitting-cam by the friction-plates 36. With this construction there is a positive connection between the cam-cylinder and sinker cam-ring holding them always in fixed relation to each other, and the head may be operated at high speed without shock or jar and without danger of the sinker cam-ring getting out of proper relation with the cam-cylinder, as in machines in which there is lost motion be-
- tween the cam-cylinder and sinker cam-ring and in which a friction is applied to the sinker cam-ring to prevent the displacement thereof.
- When the cam-cylinder is reciprocated in knitting the heel and toe, the thread-guide is shifted from one side of the knitting-cam to the other by means of a stop in the form of a plate 42, secured to the sinker-ring 19 on the needle-cylinder upon the side where the inactive needles are located, which plate is engaged by a projection on the ring 33 near the end of each stroke of the cam-cylinder in either direction and arrests the movement of the ring 33 during the last part of the stroke of the cam-cylinder. This arresting of the plate 33 while the cam-cylinder continues its movement causes the thread-guide to be shifted to the opposite or rear side of the knitting-cam, which rear side becomes the front side when the cam-cylinder begins its return stroke. The projection on the ring 33 for engaging the plate 42 is in the form of a slide 43, mounted to move radially in an arm 44, extending downward from the post 31, Fig. 1.
- During rotary knitting the slide 43 is drawn outward, so that it passes by the plate 42 as the cam-cylinder rotates. When the motion of the cam-cylinder is changed from rotary to reciprocating, the slide is moved inward, so that it will engage the plate 42. The operation of the devices will be understood from an inspection of Figs. 10 to 13. Suppose the cam-cylinder to be moving as indicated by the arrows, Figs. 10 and 12, the thread-guide will be in advance of the knitting-cam as the cam operates the active needles. After the knitting-cam has passed beyond the active series of needles and as the cam-cylinder is nearing the end of its stroke in this direction the slide 43 strikes the plate 42, as indicated in dotted lines, Fig. 10, thus arresting the movement of the ring 33. The cam-cylinder continues to move, however, and the ring 33 is shifted on the sinker cam-ring until it occupies the position with relation to the knitting-cam and sinker cam-ring. (Indicated in Fig. 11.) This brings the thread-guide 30 on the opposite or rear side of the knitting-cam or upon the left side in Fig. 12. The cam-cylinder is now reversed, and the left side of the knitting-cam, on which the thread-guide is, becomes the front side of the cam. As the cam-cylinder moves in the direction of the arrows, Figs. 11 and 13, the thread-guide therefore travels in advance of the knitting-cam until the cam has passed beyond the active needles, when the slide 43 engages the opposite side of plate 42, as indicated in dotted lines in Fig. 11, thus causing the thread-guide to be returned to the right side of the knitting-cam preparatory to the next stroke of the cam-cylinder from left to right.
- As has already been explained, the needles on the right of the wave 18 move downward

and those on the left rise as the cam-cylinder moves from left to right, and when the cam-cylinder moves from right to left the needles on the left of the wave move downward and those on the right rise. It follows, therefore, that when the cam-cylinder is moving from left to right the sinkers should be withdrawn at the right of the knitting-point where the needles are moving downward and should be in advanced position at the left of the knitting-point where the needles are rising and that the sinkers should be withdrawn at the left and advanced at the right of the knitting-point when the cam-cylinder is moving in the opposite direction or from right to left—that is, the points at which the sinkers are withdrawn and advanced should be shifted from side to side of the knitting-wave as the cam-cylinder reciprocates. The means shown for causing the sinker-cams to thus operate the sinkers is as follows: Two slides 45 and 46 are mounted to move radially in the sinker cam-ring and are connected with the pivot-pins connecting block 26 with blocks 25 and 27, Figs. 14, 16, and 17. These slides are provided with pins 47 and 48, which pass up through slots in the sinker cam-ring and are arranged to be operated upon by cams 49, 50, secured to the ring 33, the ring being cut away, as indicated in Fig. 15. The plates on which the cams 49 and 50 are formed are located between the upper surface of the ring 33 and the plate 32 and are held in place by the screws which secure the plate 32 to the ring 33.

When the cam-cylinder is moving from left to right, as in Figs. 10 and 12, the cam 49 acts upon pin 47 to hold the slide 45, so that the pivot between the blocks 27 and 26 is in its outer position and the pivot between blocks 25 and 26 is in its inner position. The block 27 will now act to withdraw the sinkers which will be advanced again by the block 26. When the ring 33 is shifted, as before explained, the cam 50 will engage the pin 48 and force the slide 46 into the inner position, as indicated in Fig. 11. This will move the pivot between blocks 27 and 26 into its inner position and move the pivot between blocks 25 and 26 into its outer position, so that when the cam-cylinder moves from right to left the block 25 will withdraw the sinkers, which will be advanced again by the block 26. When the ring 33 is shifted in the opposite direction, the blocks will be again returned to the position shown in Fig. 10 by the action of cam 49 on pin 47. The blocks are so arranged that block 25 will withdraw the sinkers on one side of the knitting-point and block 27 will withdraw the sinkers on the other side of the knitting-point, as indicated in Figs. 10 and 11.

In the construction above described the latch-guard and thread-guide are mounted upon the needle-cylinder, so that they may

be removed therewith, thus allowing the needle-cylinder to be removed and replaced without turning back the latch-guard and without withdrawing the thread from the thread-guide.

In the construction shown the needles are transferred from the active to the idle series, and vice versa, during the reciprocation of the cam-cylinder to effect the narrowing and widening by pickers of novel construction and arrangement, and these pickers are thrown into and out of operation by devices which are also novel in construction and arrangement.

The construction and arrangement of the pickers for raising individual needles from the active series during the reciprocation of the cam-cylinder is best shown in Figs. 5, 8, 9, 20, and 21. There are two pickers 51 and 52 of similar construction located upon opposite sides of the cams for reciprocating the needles. The picker 51 at the left of the knitting-cam is provided with a notched end presenting a vertical shoulder for engagement with the needle-butts and a horizontal lip for engaging the under side of the butt and lifting said butt out of the active series. The picker is mounted to slide and turn on a horizontal rod 53, located within the cam-cylinder and back of the cam-plate 11, Fig. 5. The picker is forced yieldingly toward the forward end of the rod and also down upon the upper edge of the plate 15, which is recessed to receive it, by a coiled spring 54, which surrounds the rod 53 and has one end secured to the support for the rod and the other end secured to the picker. When the needle-butt engages the notch in the picker, the picker is forced rearwardly along the rod against the tension of the spring, and means are provided for turning the picker about the rod as it is thus moved by engagement with the needle-butt, so that the lip of the picker lifts the needle-butt and transfers it to an inclined cam 55, formed on the plate 11, by which the upward movement of the needle-butt into the inactive series is completed. In the construction shown this means consists of an inclined edge or cam 56 on the picker, which is arranged to ride over the rear edge of the plate 11, the rear side of the plate being beveled off, as indicated in Figs. 8 and 9, to properly cooperate with the inclined edge of the picker in turning the picker upward and outward as it is moved by the needle-butt. The turning of the picker about the rod carries the end of the picker outward until the needle-butt passes by the end of the picker, as indicated in Fig. 9, when the picker is swung downward by the spring 54 until it rests upon the top of the needle-butts of the active series, along which it rides until it has passed all said butts and then swings down against the upper edge of the plate 15. On the return stroke of the cam-cylinder the

first needle-butt in the active series after it comes up the incline 17 strikes the back of the picker, which swings up to allow the butt to pass and rides over the butts until they have all passed, when it is swung down into the position shown in Figs. 8 and 20, ready to lift the first needle on the next stroke of the cam-cylinder from right to left. The picker 52 is of similar construction, being provided with an inclined edge 56^a, which engages the edge of an inclined cam-surface 57 on the plate 11 and being mounted upon a rod 58 and acted upon by a spring 59. There are also two pickers 60 and 61 for depressing individual needles during the widening, which are similar in construction and mode of operation to the lifting-pickers. The picker 60 is mounted on a rod 62, carried by the cam-cylinder, and is provided with an inclined edge or cam 63, which co-operates with the edge of an inclined cam-surface 64, formed on the guard-plate 65, Figs. 6, 7, and 21, and the picker 61 is mounted on a rod 66, carried by the cam-cylinder, and is provided with an inclined edge or cam 67, which co-operates with the edge of an inclined cam-surface 68 on the guard-plate 69. The pickers 60 and 61 are held yieldingly in position to engage the butts of the inactive needles by springs 70, which hold the pickers forward against collars 72 and upward against stops 74. On the forward stroke of the picker it acts to depress the needle-butts at the end of the inactive series and then rides under the needle-butts until they have all passed, and on the return stroke of the picker it is swung downward by the engagement of the needle-butts with the rear side of the picker and rides under the needle-butts, as indicated at 61, Fig. 21, until the butts have all passed, when it swings up into position, as indicated at 60, Fig. 21.

In the construction shown the depressing-pickers are provided with lips formed to engage and depress two adjacent needles, and the lifting-pickers are continued in operation during the widening operation. The general operation of narrowing and widening is well understood and will not be described in detail.

The pickers are thrown into and out of operation at the proper times by means of the guard cam-plates 65 and 69, which are so mounted that they may be moved to engage either the lifting-pickers or the depressing-pickers, and this manner of controlling the operation of the pickers forms one of the features of the present invention. The guard-plate 69 is secured to a slide 76, Fig. 24, guided in a slot 77, formed in a block 78, mounted inside the cam-cylinder, and is provided on its outer side with a thin plate 79, arranged outside the path of the needle-butts and in position to engage the end of the lifting-picker 51. The guard-plate 65, Figs. 19 to

21, is secured to a similar slide guided in a slot 80 and is provided with a similar plate 81, arranged to engage the end of picker 52.

The guard-cam 69 is operated through a plate 82, secured to the slide 76 and provided with a depending arm 83, which passes through a hole in a plate 84, secured to a slide 85. The slide 85 is guided between the cam-cylinder and ledge 9, as shown in Fig. 26. The slide 85 is provided with a radially-extending slot 86, which is engaged by a crank-pin 87 on a disk 88, secured to a vertical shaft 89, mounted on the cam-cylinder. The guard-cam 65 is operated through a similar plate 90, connected with a similar slide 91, which is provided with a radial slot 92, engaged by a crank-pin 93 on a disk 94, secured to the crank-pin 87, the crank-pin 93 being diametrically opposite the crank-pin 87, Fig. 5.

During rotary knitting the parts are in the position indicated in Figs. 5 and 19, with the guard-cams 65 and 69 in their forward position against the inclined ends of the plate 11. In this position the guard-cams act to direct any raised needle-butt onto the ledge 9 and to prevent any needle-butt rising above the ledge as it passes off the cam 16—that is to say, they act as guard-cams for insuring the proper movement of the needle-butts. They also act to hold the lifting-pickers back out of the path of the needle-butts. When the narrowing is to begin, the shaft 89 is given two quarter-turns. The first quarter-turn moves the guard-cams into the position shown in Fig. 21, thus leaving the lifting-pickers free to swing down into operative position. The second quarter-turn of the shaft draws the guard-cams into the position shown in Fig. 20. As the cams move into this position they engage the rear sides of the depressing-pickers 60 and 61 and turn them down out of the path of the needle-butts, as indicated. When the narrowing is completed, the shaft 89 is given a third quarter-turn, bringing the guard-cams into the position shown in Fig. 21, thus leaving both the lifting and depressing pickers free to swing into operative position. When the widening is completed, the shaft is given a fourth quarter-turn, bringing the parts back into the position shown in Fig. 19. As the guard-cams move into this position the plates 79 and 81 engage the outer ends of the pickers 51 and 52 and force them along their guiding-rods, so that they are turned upward and outward behind the guard-cams and plate 11.

The construction of the cam for throwing the needles not used on the heel and toe and the manner of operating the cam is novel and embodies features of invention. The needles are thrown out of and into operation by a swinging cam 95, Figs. 1, 4, 19 to 21, and 27 to 29, which is secured to the inner end of a shaft 96, mounted on the cam-cylinder above the shaft 89. The cam is provided with two

guiding-surfaces 97 and 98, the surface 97 acting to depress the butts of the inactive needles onto the ledge 9 and the surface 98 acting to raise the long butts of the needles not used on the heel and toe up into the inactive level above the knitting and guard cams. In order that the cam may act only upon the long butts when raising the needles and may be in position to act upon both long and short butts when depressing the inactive needles, means are provided for moving the cam radially of the cam-cylinder, as well as for giving it a swinging movement. The cam is given a radial movement as it swings from one position to the other by V-shaped cams 99, formed on a stationary sleeve 100, surrounding the shaft 96, the cams being arranged to engage V-shaped notches 101 in the hub of the cam 95. The cam is swung from one position to the other through a rocking sleeve 102, surrounding the shaft 96 and connected therewith by a key 102^a, which extends through the shaft and through longitudinal slots 103 in the sleeve. The sleeve 102 is rocked at the proper time by a radially-projecting arm 104, secured to the slide 91 and arranged to act upon two arms 105 and 106, projecting from the sleeve 102. A spring 107 is interposed between the end of sleeve 102 and a cap 108 on the end of shaft 96 and tends to draw said shaft radially outward.

During rotary knitting the cam 95 stands in the position shown in Figs. 19 and 27 to 29, with the hub of the cam against the ends of cams 99, so that the surface 97 is in position to engage both the short and long butts. The arm 104 at this time lies under the arm 106, Fig. 29. When the shaft 89 is given the two quarter-turns as the motion of the cam-cylinder is changing from rotary to reciprocating, the arm 104 is moved from the full-line position, Fig. 29, to the dotted-line position, and in this movement it strikes arm 105 and swings it into dotted-line position, thus swinging the cam 95 into the position shown in Fig. 20. As the cam 95 swings into this position the notches 101 are brought into line with cams 99, allowing the spring 107 to draw the cam 95 radially outward into the dotted-line position, Fig. 27, where the surface 98 will engage only the long butts. The third quarter-turn of shaft 89 moves arm 104 into mid-position between arms 105 and 106. When the shaft 89 is given its last quarter-turn, the arm 104 strikes arm 106 and returns the parts to the position shown in Figs. 19, 27, and 29, so that the surface 97 depresses the long butts and any short butts which may not have been depressed by the depressing-pickers.

The shaft 89 is operated at the proper times by means of a star-wheel 109, secured thereto, which is provided with four radial projections 110, arranged to engage a vertically-movable finger 111 when said finger

is depressed. In case the knitting-head is used in an automatic machine the finger will be automatically moved into the path of the star-wheel just before the motion-changing mechanism is operated, so that the star-wheel will strike the finger twice while going in the same direction, thus giving the wheel two quarter-turns. The finger will then be raised until the narrowing is completed, when it will be moved into the path of the star-wheel and will be raised again after being once engaged by the wheel, which operation will be repeated at the end of the widening. The shaft is held in its different positions by spring-pressed pins 109^a, having conical ends arranged to engage recesses 110^a in the star-wheel.

The head shown is designed for use in an automatic machine, and means are therefore provided for automatically moving the slide 43, heretofore described, radially inward at the beginning of reciprocating knitting and for withdrawing said slide at the end of reciprocating knitting. The means shown for doing this consists of a swinging plate 112, Figs. 1, 4, and 23, pivoted on the shaft 41 and frictionally held from movement by a spring 113, interposed between the plate and the head of a screw 114, which passes through a slot in the plate. The plate 112 is connected with the slide 43 by means of a slot 115, which is engaged by a pin 116 on the slide. The plate is swung inward and outward about its pivot by means of a pin 117, projecting upward from the plate 82, heretofore described, and working in a cam-opening 118 in the plate 112. The cam-opening is provided with two surfaces 119 and 120, substantially concentric with the cam-cylinder, and with two inclined or cam surfaces 121 and 122.

During rotary knitting the parts are in the position shown in Fig. 4. The slot 115 is so arranged that when the parts are in this position the forward end 115^a of the slot in which the pin 116 lies is in position to hold the slide 43 in its outer position, where it will not engage plate 42, the slot being so constructed that when the plate 112 is swung into its inner position the slot will be concentric with the cam-cylinder and will be in position to hold the slide 43 in the inner position. When the shaft 89 is given the first two quarter-turns above referred to, the pin 117 engages the cam-surface 121 and swings the plate 112 inward, thus moving the slide 43 into position to engage plate 42 and bringing the slot 115 into position concentric with the cam-cylinder. Now as the ring 33 is shifted back and forth as above described the pin plays in the concentric slot 115 and the slide 43 remains in its inner position. When the shaft 89 is given its third quarter-turn, the pin 117 moves along the surface 120 and does not affect the position of plate 130.

112. When the shaft 59 is given its fourth quarter-turn, the pin 117 rides along cam-surface 122 and swirls the plate 112 outward, thus drawing the slide 43 out where 5 it will pass by the plate 42.

In addition to the features already described the knitting-head shown is provided with novel means for leveling the needles, so that a transfer-quill cup may be supported 10 on and centered by the sinkers in transferring a top to the needles when the machine is being used to knit half-hose. The manner of effecting the transfer of the top of the needles when the needles are thus leveled is 15 fully explained in Patent No. 656,218, dated August 21, 1900, to which reference may be had. In the head shown, as in the head of the patent referred to, the tops of all the needles are brought below the sinkers by directing the needle-butts into a guideway or groove inside the cam-cylinder below the knitting-cams. The major portion of this guideway 123 is formed by the under edge 20 of the ledge 9 and the upper edge of a ring 124, secured inside the cam-cylinder in the same way that ledge 9 is secured, the space between the ledge 9 and ring 124 being substantially the width of the needle-butts. In order to guide the needle-butts into this groove, the plates 14, 15, and 11 and the guard-cams 65 and 69 are mounted upon a vertically-sliding block 78. The block 78 is provided with a rib 125, which fits within a guideway 126, formed in the inner surface of 25 a curved plate 127, secured to the cam-cylinder and forming a part of its wall. The block 78 is held with the rib 125 in the guideway by a screw 128, which passes through a slot 129 in the plate 127 and has a flange 130, formed thereon, which engages a plate 131, bearing upon the outside of plate 127. The block 78 is moved vertically by means of a cam 132, secured to the shaft 41, and having a cam-groove which engages the outer end 30 of the screw 128. The shaft 41 is mounted in a bracket 133, secured to the outer surface of the plate 127, and is provided with a handle 134, by which it may be turned. The shaft 41 is held in its normal position by a spring 135, Fig. 5, which bears upon a flat place 136 on the cam 132.

When the needle-butts are to be directed into the groove 123, the shaft 41 is turned and the cam 132 raises the block 78 until the 35 parts are in the position shown in Fig. 22. This brings the under sides of the plates 14 and 15 into line with the under edge of ledge 9 and brings the upper surface of a rib 137, which is secured to the block 78, into line 40 with upper surface of ring 124, the space between the rib 137 and plates 14 and 15 forming a part of the groove for leveling the needle-butts. The cam-cylinder is then revolved in the direction of the arrow, Fig. 22, 45 and the needle-butts on the ledge 9 pass

down the inclined cam-surface 138 on the plate 15 into the guideway 123, those needle-butts which are lifted by the upward movement of the plates 14 and 15 being depressed onto the ledge 9 by the cam 95 and also passing down the incline 138. After the top has been transferred to the needles in the manner set forth in the Patent No. 656,218, referred to, the block 78 is returned to its lower position, bringing the parts into the position 75 shown in Fig. 19. The needle-butts are returned into knitting position by a cam 139, secured to the ring 124 and arranged to project above the rib 137 and between the adjacent ends of the plates 14 and 15. As the 80 cam-cylinder is rotated the needle-butts in the grooves 123 pass down the incline 138 under the plate 15 and up the cam 139 onto the incline 16, the butts which were carried down by the depression of the plate 14 passing up a cam-surface 140 into the guideway 85 123.

The space between the ends of plates 14 and 15 is bridged over by a yielding mounted bridge 141, which is mounted to slide radially in a recess in the block 78, Fig. 1. The bridge is provided with an inclined under side 142, which bears upon the inclined upper edge of cam 139. The bridge-piece 141 is loosely mounted in its recess, so that it may have a slight vertical play, and is pressed forward by a spring 143. The bridge is held up in position by the engagement of its incline 142 with the cam 139. During the knitting the needle-butts pass over the upper surface. 90 When the butts are forced upward by the cam 139, they strike the under side 142 and force the bridge-piece back, so that they may pass by said piece onto the cam 16. The bridge 141 also forms a yielding cushion during the knitting for arresting the downward movement of the needle-butts and holding them up against the end of the knitting-cam. This construction enables the head to be operated at a high rate of speed and insures a uniform fabric, since the extent of the downward movement of the needle is determined by the end of the knitting-cam and the downward movement of the needle is arrested by the cushion and not by the resistance of the 105 loop being drawn.

For convenience in setting up the machine and in removing the parts for repair it is preferred to mount the pickers as well as the cams for guiding the needle-butts during the 110 knitting upon the block 78 and to so mount the block that it may be readily removed with the attached parts. This result is accomplished in the construction shown in which the section 127 of the cam-cylinder 115 supports the block 78 and the parts attached thereto. This section may be readily removed by removing the screws by which it is attached to the cam-cylinder.

While I have described the features of in- 130

vention in connection with a knitting-head in which the knitting-wave is caused to travel about the needles by rotating the cam-cylinder, it will be understood that the travel of the wave may be produced by rotating the needle-cylinder, in which case the cam-cylinder would be stationary.

With relation to the turning of the pickers upon their axes as they are moved longitudinally thereof, it is not necessary that the surface with which the pickers engage in turning shall be a cam-surface, because the picker itself is provided with a cam-surface on its rear side, and the engagement of this cam-surface with any suitable surface would serve to give the requisite turning movement to the picker as it is moved lengthwise on its axis.

What I claim as my invention, and desire to secure by Letters Patent, is—

1. In a knitting-machine the combination of a circularly-arranged series of needles, a single knitting-cam for operating the needles to draw the loops during reciprocating knitting, sinkers for holding the fabric as the needles advance through the loops, means for advancing and withdrawing the sinkers and means for leading the thread to the needles in advance of the knitting-point as the knitting-wave travels back and forth along the series of needles, substantially as described.

2. In a knitting-machine the combination of a needle-cylinder, needles guided therein, a cam-cylinder provided with means for forming a knitting-wave in the needles in fixed relation to the cam-cylinder during reciprocating knitting, sinkers for holding the fabric as the needles rise, means for advancing and withdrawing the sinkers and means for leading the thread to the needles in advance of the knitting-wave during the travel of the wave in either direction, substantially as described.

3. In a knitting-machine the combination of a needle-cylinder, needles guided therein, a cam-cylinder provided with means for forming a knitting-wave in the needles in fixed relation to the cam-cylinder during reciprocating knitting, sinkers for holding the fabric as the needles rise, means for shifting the points at which the sinkers are advanced and withdrawn from side to side of the knitting-wave, and means for leading the thread to the needles in advance of the knitting-wave during the travel of the wave in either direction, substantially as described.

4. In a knitting-machine the combination of a needle-cylinder, needles guided therein, a cam-cylinder provided with a single knitting-cam for operating the needles to draw the loops during both rotary and reciprocating knitting, sinkers for holding the fabric, means for shifting the points at which the sinkers are withdrawn and advanced from side to side of the point of the knitting-cam

during reciprocating knitting, and means for shifting the point from which the thread is led to the needles from side to side of the knitting-cam, during reciprocating knitting, substantially as described.

5. In a knitting-machine the combination of a needle-cylinder, needles guided therein, a cam-cylinder provided with a single knitting-cam for drawing down the needles during rotary and reciprocating knitting, sinkers for holding the fabric, a sinker cam-ring provided with movable cams for reciprocating the sinkers, and means for shifting the sinker-cams during reciprocating knitting, substantially as described.

6. In a knitting-machine the combination of sinkers for holding the fabric, a sinker cam-ring, cams movably mounted on said ring for operating the sinkers, and means for shifting said cams radially during the reciprocation of the sinker cam-ring, substantially as described.

7. In a knitting-machine the combination of sinkers for holding the fabric, a sinker cam-ring having an annular rib for engaging the sinkers, pivoted blocks forming a part of said rib and means for operating said blocks to vary the operation of the sinkers, substantially as described.

8. In a knitting-machine the combination of sinkers for holding the fabric, a sinker cam-ring having movable cams for operating the sinkers, a slide frictionally held on the sinker cam-ring, connections between the slide and sinker-cams whereby the movement of the slide shifts said cams, and means for shifting said slide on the sinker-cam ring at the end of the stroke in each direction of the reciprocation of the sinker cam-ring.

9. In a knitting-machine the combination of a needle-cylinder, needles guided therein, a cam-cylinder provided with a single cam for drawing down the needles during rotary and reciprocating knitting, sinkers for holding down the fabric, means for advancing and withdrawing the sinkers, a thread-guide connected with the cam-cylinder, and means for shifting the thread-guide from side to side of the knitting-cam during reciprocating knitting, substantially as described.

10. In a knitting-machine, the combination of a needle-cylinder, needles guided therein, a cam-cylinder carrying a single knitting-cam for operating the needles to draw the loops during both rotary and reciprocating knitting, sinkers for holding the fabric, means for advancing the sinkers back of the knitting-point as the cam-cylinder reciprocates, and means for leading the thread to the needles from in front of the wave formed in the needles, substantially as described.

11. In a knitting-machine the combination of a cam-cylinder, a thread-guide frictionally connected to move with said cam-cylinder, a radially-movable slide connected with the

- thread-guide, and a stop arranged to be engaged by the slide as the cam-cylinder approaches the end of its stroke in either direction, substantially as described.
- 5 12. In a knitting-machine the combination of a cam-cylinder, a thread-guide movably connected therewith, means for arresting the movement of the thread-guide before the cam-cylinder reaches the end of its stroke in either direction, and means for automatically rendering said arresting means inoperative during rotary knitting, substantially as described. 70
13. In a knitting-machine the combination of a cam-cylinder provided with a single knitting-cam, sinkers for holding the fabric, a sinker cam-ring connected with the cam-cylinder and provided with movable cams for operating the sinkers, a thread-guide movably connected with the cam-cylinder, means for shifting the thread-guide with relation to the cam-cylinder and means for shifting the sinker-cams through the movement of the thread-guide, substantially as described. 75
- 25 14. In a knitting-machine, the combination, with a needle-cylinder and needles guided therein, of a cam-cylinder provided with a single knitting-cam for forming a knitting-wave in said needles, means for rotating and reciprocating one of said cylinders, sinkers, a sinker cam-ring, and means for positively connecting the cam-cylinder and sinker cam-ring in fixed relation, and means for changing the relation between the knitting and sinker-operating cams during reciprocating knitting, substantially as described. 80
- 30 15. In a knitting-machine, the combination of a needle-cylinder, needles guided therein, a cam-cylinder provided with a single knitting-cam for drawing down the needles during rotary and reciprocating knitting, sinkers for holding the fabric, and a sinker cam-ring provided with cams for advancing the sinkers back of the knitting-point and withdrawing the sinkers, substantially as described. 85
- 45 16. In a knitting-machine, the combination of a rod, a picker mounted to slide and swing upon said rod, a spring for holding the picker in position to be engaged by the needles, and a cam for swinging the picker about the rod as it is moved longitudinally of the rod by engagement with the needles, substantially as described. 90
- 55 17. In a knitting-machine the combination of a picker mounted to swing about an axis and to be moved longitudinally of its axis by engagement with the needles, and means rendered effective by the longitudinal movement of the picker imparted to it by the needle for swinging it about its axis, substantially as described. 95
- 60 18. In a knitting-machine the combination of a horizontal rod, a picker mounted to slide and swing upon said horizontal rod, a spring for holding the picker in position to be engaged by the needles, and a cam for swinging the picker about the rod as it is moved longitudinally of the rod by engagement with the needles, substantially as described. 100
- 70 19. In a knitting-machine the combination of a picker mounted to swing about an axis and to be moved longitudinally of the axis by its engagement with the needles, a cam on the picker for swinging the picker and a co-operating surface over which the cam rides when the picker is moved longitudinally by engagement with the needles, substantially as described. 105
- 75 20. In a knitting-machine the combination of a picker mounted to swing about an axis and to be moved longitudinally of the axis by its engagement with the needles, of a cam to which the needles are transferred by the picker, and means for swinging the picker in back of the cam as the picker is moved longitudinally by its engagement with the needles, substantially as described. 110
- 80 21. In a knitting-machine the combination of a picker mounted to swing about an axis and to be moved longitudinally of the axis by its engagement with the needles, of a cam to which the needles are transferred by the picker, a cam-surface on the picker which cooperates with the edge of said cam to swing the picker out of the path of the needles as the picker is moved longitudinally by its engagement with the needles, substantially as described. 115
- 85 22. In a knitting-machine the combination of a picker for operating upon the needles, a cam to which the needle is transferred by the picker, and means for moving said cam to throw the picker into and out of operation, substantially as described. 120
- 90 23. In a knitting-machine the combination of a lifting-picker, a depressing-picker, a guard-cam, and means for moving said guard-cam to engage and throw either picker out of operation. 125
- 95 24. In a knitting-machine the combination of a lifting-picker, a depressing-picker, a guard-cam normally holding the lifting-picker out of operation, means for moving said guard-cam to release the lifting-picker and to throw the depressing-picker out of operation at the beginning of the heel and toe, to release the depressing-picker at the beginning of the widening and to throw the lifting-picker out of operation to the end of the widening, substantially as described. 130
- 100 25. In a knitting-machine the combination of a guard-cam, a slide to which the cam is secured, a second slide to which the former slide is connected, a radial slot in said second slide, a crank-pin engaging said slot, and means for intermittently rotating said crank-pin, substantially as described. 135
- 105 26. In a knitting-machine the combination of a cam provided with cam-surfaces for rais-

ing and depressing the needles, means for automatically swinging said cam about its axis to bring either of said surfaces into operation, and means for moving said cam radially inward when the depressing-surface is to operate, and radially outward when the raising-surface is to operate, substantially as described.

27. In a knitting-machine the combination of a cam provided with cam-surfaces for raising and depressing the needles, means for automatically swinging said cam about its axis, and a stationary cam for moving said needle-operating cam longitudinally of its axis as it is swung about its axis, substantially as described.

28. In a knitting-machine the combination of the cam-cylinder provided with a leveling-guideway, a vertically-movable block carrying the cams for reciprocating the needles, and a cam carried by said block which is brought into the path of the needle-butts by the upward movement of said block and directs the needle-butts into said guideway, substantially as described.

29. In a knitting-machine the combination of the cam-cylinder, provided with a leveling-guideway, a vertically-movable block carrying the cams for reciprocating the needles, a cam carried by said block which is brought into the path of the needle-butts by the upward movement of said block and directs the needle-butts into said guideway, and a cam for directing the needle-butts out of said guideway when said block is depressed, substantially as described.

30. In a knitting-machine the combination of a cam-cylinder, provided with a leveling-guideway, a vertically-movable block carrying the cams for reciprocating the needles, a cam-surface on said block for directing the needle-butts into the guideway when the block is raised, a cam arranged to direct the needle-butts onto one of the cams for raising the needles when the block is depressed and a yielding bridge above the latter cam, substantially as described.

31. In a knitting-machine the combination of a cam-cylinder provided with a leveling-guideway, a vertically-movable block, cam-plates 11, 14 and 15 carried by said block, a cam-surface 138 on plate 15, a rib 137 carried by said block below the plates 14 and 15, and a cam 139, substantially as described.

32. In a knitting-machine the combination of a cam-cylinder, a ledge for the needle-butts supported within and out of contact with the inner surface of the cam-cylinder, and knitting-cams supported inside the cam-cylinder to leave a free space between said cams and the cam-cylinder for the escape of broken needle-butts, substantially as described.

33. In a knitting-machine the combination

of a knitting-cam and a yielding cushion below said cam, substantially as described.

34. In a knitting-machine the combination of a knitting-cam, and a spring-pressed bridge-piece 141 at the end of the knitting-cam, substantially as described.

35. In a knitting-machine the combination with a knitting-cam adapted for rotary and reciprocating knitting, of sinkers for holding the fabric; and means for advancing and withdrawing the sinkers, substantially as described.

36. In a knitting-machine the combination with a knitting-cam adapted for rotary and reciprocating knitting, of sinkers for holding the fabric, means for advancing and withdrawing the sinkers, and means for automatically effecting the narrowing and widening, substantially as described.

37. In a knitting-machine the combination with a knitting-cam adapted for rotary and reciprocating knitting, of means for automatically throwing individual needles out of and into operative relation with said cam during the reciprocating knitting, substantially as described.

38. In a knitting-machine the combination with a knitting-cam adapted for rotary and reciprocating knitting, of means for rendering a part of the needles inactive during reciprocating knitting, and means for automatically rendering individual needles inactive and active during reciprocating knitting, substantially as described.

39. In a knitting-machine the combination with a knitting-cam adapted for rotary and reciprocating knitting, of sinkers for holding the fabric, means for advancing and withdrawing the sinkers, means for rendering a part of the needles inactive during reciprocating knitting, and means for automatically rendering individual needles inactive and active during reciprocating knitting, substantially as described.

40. In a knitting-machine the combination with a knitting-cam adapted for rotary and reciprocating knitting, of a switch-cam for rendering a part of the needles inactive during reciprocating knitting and needle-pickers for transferring individual needles from one series of needles to the other in narrowing and widening, substantially as described.

41. In a knitting-machine the combination with a knitting-cam adapted for rotary and reciprocating knitting, of needle-picking means operating in connection therewith, substantially as described.

42. In a knitting-machine the combination with a knitting-cam adapted for rotary and reciprocating knitting, of needle-picking means operating at the sides of said cam, substantially as described.

43. In a knitting-machine the combination with a knitting-cam adapted for rotary and

- reciprocating knitting, of needle - picking means operating alternately at opposite sides of said cam, substantially as described.
44. In a knitting-machine the combination with a knitting-cam adapted for rotary and reciprocating knitting, of needle - picking means coöperating with said cam to lift the needles during narrowing, substantially as described.
45. In a knitting-machine the combination with a knitting-cam adapted for rotary and reciprocating knitting, of needle - picking means coöperating with said cam to lift the needles, substantially as described.
46. In a knitting-machine the combination with a knitting-cam adapted for rotary and reciprocating knitting, of needle - picking means operable alternately at opposite sides of said cam, the latter having portions coöperating with said needle-picking means to continue the lifting movements of the needles after movement thereof by said picking means, substantially as described.
47. A knitting - machine provided with a knitting-cam adapted for rotary and reciprocating knitting presenting the same path of movement for the needles irrespective of the direction of relative movement between the same and said cam, and needle-picking means adapted to operate automatically in connection with the respective ends of said cam, substantially as described.
48. In a knitting-machine, a switch-cam, and means automatically to impart vertical and also in and out movements thereto, substantially as described.
49. In a knitting-machine employing long and short butt needles, a switch-cam, and means automatically to impart vertical and also in and out movements thereto, substantially as described.
50. In a knitting-machine the combination of a needle-cylinder, its needles, a knitting-cam adapted for rotary and reciprocating knitting, and needle-picking means operating at the sides of said cam, substantially as described.
51. In a knitting - machine the combination with a knitting-cam adapted for rotary and reciprocating knitting, sinkers for holding the fabric, means for advancing the sinkers back of the knitting-point, and means for leading the thread to the needles in front of the knitting-point, substantially as described.
52. In a knitting - machine the combination with a knitting-cam adapted for rotary and reciprocating knitting, sinkers for holding the fabric, cams for advancing and withdrawing the sinkers, and pickers for automatically effecting the narrowing and widening, substantially as described.
53. In a knitting - machine the combination with a rotary cam-carrier, of a knitting-cam secured in fixed relation thereto adapted for rotary and reciprocating knitting, sink-
- ers for holding the fabric, and means for advancing and withdrawing the sinkers, substantially as described.
54. In a knitting - machine the combination of a rotary cam-carrier, a knitting-cam secured in fixed relation thereto adapted for rotary and reciprocating knitting, sinkers for holding the fabric, means for advancing and withdrawing the sinkers, and means for automatically effecting the narrowing and widening, substantially as described.
55. In a knitting - machine the combination of a rotary cam-carrier, a knitting-cam secured in fixed relation thereto adapted for rotary and reciprocating knitting, and needle-picking means operating in connection therewith, substantially as described.
56. In a knitting-machine, stitch-forming cam-surfaces adapted for circular and reciprocatory knitting, needle-picking means, operable at opposite sides thereof, and means to deliver the thread in advance of said cam-surfaces at each reciprocation thereof.
57. In a knitting-machine, the combination with a double-acting stitch-forming cam, of needle-picking means operating in connection therewith.
58. In a knitting-machine, the combination with a double-acting stitch-forming cam of needle-picking means operating at both sides of said cam.
59. In a knitting-machine, the combination with a double-acting stitch-forming cam of needle-picking means operating alternately at opposite sides of said cam.
60. In a knitting-machine, the combination with a double-acting stitch-forming cam of needle-picking means coöperating with said cam to elevate or depress the needles during narrowing and widening.
61. In a knitting-machine, the combination with a double-acting stitch-forming cam of needle-picking means coöperating with said cam to elevate or depress the needles.
62. In a knitting-machine, the combination with a double-acting stitch-forming cam of needle-picking means operable alternately at opposite sides of said cam, the latter having portions coöperating with said needle-picking means to continue the elevating or depressing movements of the needles after movement thereof by said picking means.
63. A knitting-machine provided with a stitch-forming cam presenting the same path of movement for the needles irrespective of the direction of relative movements between the same and said cam and needle-picking means adapted to operate automatically in connection with the respective ends of said cam.

JAMES E. ROWE.
